PREPARATION OF OXYGENATED COMPOUNDS

Filed Nov. 19, 1935

UNITED STATES PATENT OFFICE

2,128,909

PREPARATION OF OXYGENATED COMPOUNDS

Joseph Elliott Bludworth, Arlington, Tex., assignor to Celanese Corporation of America, a corporation of Delaware

Application November 19, 1935, Serial No. 50,519

16 Claims. (Cl. 260—451)

This invention relates to the preparation of oxygenated compounds by processes involving the oxidation of hydrocarbons and relates more particularly to the formation of lower aliphatic oxygenated compounds in relatively large yields.

An object of my invention is to prepare oxygenated compounds by the oxidation of hydrocarbons in such a manner that the nature of the products formed may be controlled. A further object of my invention is to provide a process for the oxidation of hydrocarbons wherein the number of oxygenated compounds formed is relatively small and whereby such compounds may be separated in relatively pure form from the products of reaction. Other objects of this invention will appear from the following detailed description.

It has been proposed to form oxygenated compounds by the oxidation of hydrocarbons. However, in such prior processes, the number of oxygenated compounds formed in the reaction is very large with the result that it is practically impossible to separate them into commercially pure components. Moreover, the yields of desired lower aliphatic compounds, such as acetaldehyde, acetone, methyl alcohol, etc., have been relatively small. I have found that if the oxidation of the hydrocarbons is permitted to proceed over a relatively large range of temperatures and for a relatively extended period of time, secondary reactions causing the formation of the large number of oxygenated compounds take place.

On the other hand, I have found that if the oxygenation process is allowed to proceed for a relatively short time under conditions whereby the hydrocarbon is raised to the desired reaction temperature, large yields of lower aliphatic oxygenated compounds are produced, the number of which compounds is relatively small whereby the compounds may be separated into relatively pure state quite readily. Whereas, heretofore, oxidation reactions have produced a large number of compounds in small amounts, I have found that by varying the conditions of oxidation so that the reaction time is short the lower molecular weight more desirable compounds are produced in larger quantities.

Moreover, I have found that if a large amount of diluent, such as steam, nitrogen or other inert gas or vapor is present during the oxidation process, such diluent prevents or diminishes undesirable reactions and formation of undesired products by absorbing the heat generated during the oxidation process and thus preventing the rise of temperature to the point where such undesired

reactions take place. While nitrogen or low boiling hydrocarbons may be used as a diluent, steam is preferred as it presents a protective influence not enjoyed by other diluents.

Conveniently, the process may be carried out by separately heating a relatively large amount of steam or other diluent to the high temperature required for the reaction and then mixing therewith the hydrocarbon to be oxygenated and the required amount of air or other oxygen-containing gas under conditions whereby rapid and thorough mixing is attained. Prior to admixture with the heated steam, the hydrocarbon and air may or may not be preheated, but if it is preheated it should be at a temperature below the decomposition point thereof. Upon this mixing of the hydrocarbon with the heated steam, the entire mass is brought to the reaction temperature and oxygenation of the hydrocarbon takes place. After the oxygenation reaction is initiated, the steam serves the purpose of maintaining dilution and by absorbing heat acts as a heat dampener to prevent rise of temperature to an undesired extent. The steam is employed as a diluent, a dampener to prevent excessive heat generated by the reaction and also a substance used as a protective element for the products of oxygenation. Also, the steam is used as a heat transfer agent.

The time during which the oxidation reaction is permitted to occur should be sufficiently short so as to inhibit the setting in of decomposition reactions that tend to form undesirable products. Ordinarily the reaction is permitted to proceed for a period of 0.1 to 3 seconds, preferably 0.3 to 0.5 second. The time at which the mass is permitted to remain at the temperature of reaction is conveniently controlled by spraying or otherwise injecting water or other cooling liquid into the reaction mass in sufficient quantities to quench the gases and vapors so as to reduce the temperature thereof to below the decomposition temperature and preferably below 350° F. The resulting vapors and gases are then conducted to a suitable system for the recovery and separation of the oxygenated products formed.

While I prefer to employ butane as the hydrocarbon to be oxygenated, other hydrocarbons such as propane, pentane, light petroleum distillates, gas oil, etc., either alone or in admixture with each other, may be oxygenated by this process.

The amount of steam, nitrogen or other gas used as heat transfer agent, diluent and heat dampener is large in order to control the reaction

properly, and is from 30 to 200 or more, preferably 50 to 100, parts by gas volume per one part by gas volume of the hydrocarbon gas or vapor to be oxygenated.

- 5 The amount of oxygen employed in the reaction is also of importance in determining the nature and yields of the oxygenated product formed. For the best results, the amount of oxygen employed is that equivalent to that present 10 in 7 to 14, preferably 7 to 10, parts by gas volume of air per one part by gas volume of the hydrocarbon gas or vapor to be oxygenated. By increasing the amount of diluent gas present the amount of oxygen employed may be increased. 15 The amount of oxygen may vary between the explosive limits by a corresponding variance in amount of diluent employed.

The heating medium whether steam, air or a mixture of steam and air or other diluent should 20 be raised to suitable temperatures, say 1,000° F. or more immediately prior to admixture with the hydrocarbon, such that when mixed with the hydrocarbon the temperature will be from 550° to 850° F. and preferably 750° to 800° F.

- 25 The hydrocarbon may be preheated prior to admixture with the air and steam, but should be preheated to a temperature below that at which decomposition tends to take place.

In order to obtain rapid heating of the hydrocarbon and consequently rapid reaction, the air and steam and the hydrocarbon are caused to approach at a high velocity to a suitable mixing device that causes mixing at high turbulence.

The reaction is preferably conducted under 35 super-atmospheric pressures, say on the order of 25 to 500 pounds per square inch. Generally, 50 to 200 pounds per square inch pressure are sufficient to produce the desired results.

By my process, there are formed products of 40 great commercial value and which can be separated into pure or substantially pure chemical compounds, such as a acetaldehyde, formaldehyde, acetone, methyl alcohol, acetic and other organic acids as well as small proportions of methyl, 45 propyl and butyl alcohol.

The accompanying drawing shows diagrammatically a form of apparatus that may be used in carrying out the invention.

There is provided a pipe 1 for introducing water into the system. Pipe 1 leads to a meter 9 and then to a pump 69. A pipe line 22 is provided to carry the water from the pump 69 to a quench chamber 23. The quench chamber 23 is so constructed that the products of the reaction 55 may be cooled from the elevated temperature of reaction to about 320° F. or less.

There is a pipe 2 through which steam may be introduced into the system, which pipe may pass through a metering device 8 and into a 60 superheater-furnace 12. The superheater furnace 12 may be provided with a coil 13 for carrying the steam therethrough. The heating coil 13 may be connected by a pipe to a mixer 17. The pipe for carrying the steam from the heating coil 13 to a mixer 17 may be provided with a 65 temperature recorder 14.

A pipe or other conduit 3 may be provided for introducing air or other oxygen-containing gas into the system. Pipe 3 may pass through a 70 meter 7 and compressor 16 into the mixer 17.

A pipe 4 may be provided for introducing butane or other hydrocarbon into the system. The pipe 4 may pass through a vaporizer 5, a 75 metering device 6 and then to the inlet of the compressor 16. A pipe 15 may be provided for

introducing recycle gas to the compressor 16. The course of the recycle gas will be hereinafter set forth.

At the mixer 17 the air, hydrocarbon, recycle gas and steam may be admixed. The use of 5 superheated steam produced in the superheater 12 not only aids in the heating of the mixture but also acts to maintain the same at a constant temperature. The mixture of reacting gases is led from the mixer 17 to a reaction chamber 19. 10 The conduit leading from the mixer 17 to chamber 19 may be provided with a temperature registering device 18. The reaction chamber 19 comprises a reaction zone 20 for the reacting gases. The reaction chamber 19 may be enclosed in a 15- heater jacket. The point of initiation of reaction may be determined by the readings of thermometers 21, a number of which are inserted at regular intervals throughout the length of the reaction zone 20. The heated and reacted gases 20 pass from the reaction zone 20 to the quench chamber 23 where the latent heat is removed from the gases and the temperature thereof is reduced from the temperature of reaction to about 320° F. or less. In place of the furnace, 25 shown as the reaction chamber 19, any suitable means may be employed to maintain the reaction zone 20 at a constant temperature. An alternative means may be the mere insulation of the reaction zone 20.

30 A pipe or conduit 24 may be provided for carrying the products of reaction from the quench chamber 23 to a cooler 25. The temperature of the quenched reaction gases may be indicated by a temperature indicator placed in the line 24. 35 The cooler 25 acts to control the temperature of the reaction products and to remove sufficient specific heat to follow the mixture of gases, water and other products of reaction to pass to an accumulator and absorber 28 at the proper temperature 40 for purposes of crude distillation. A pipe or conduit 32 may be provided leaving from the absorber 28 to a still 35. Suitable temperature recording devices 26 and 30 may be inserted into the feed and discharge lines of the absorber 28. 45 For the purpose of regulating the level of the liquids in the system a valve 31 is placed in pipe 32.

In the absorber 28 the liquid and gaseous reaction products and also the uncombined elementary gases of the mixture are separated. The liquid portion passes through the line 32 to the 50 still 35. The gases pass out of the still by way of a pipe line 29. The liquids leaving the absorber 28 through the pipe 32 may be mixed at 33 with a very small amount of water previously 55 used to absorb the product contained in the "tall" gases from the distillation system. The liquids, leaving the absorber 28 through the pipe 32, and the water injected into the system at 33 are led through a conduit or pipe 34 to the still 35, where 60 such products of the reaction as acetaldehyde, acetone and alcohols together with some water are flashed off overhead. By means of suitable pipes the remainder of the liquid fraction of the reaction products, which liquid fraction comprises 65 organic acids, formaldehyde and water, pass to a re-boiler 36. The re-boiler 36 may be provided with a pipe 37 through which said boiler may be drained to waste or the liquids contained therein may be passed to further treatment. Gases liberated in the re-boiler may be returned through 70 a suitable pipe to the bottom of the still 28.

The still 35 may be connected in any suitable manner with a dephlegmator 38 which is provided with a pipe 39 connecting it with a con- 75

denser 40. The products of the still or flash column 35 pass through the dephlegmator 38 to the final condenser 40. The condensed product from the condenser 40 may be passed by means 5 of a pipe 41 to the crude distillate storage tank 42. The distillate in the storage tank 42 may be led to stills, not shown, for final refining.

The crude distillate storage tank 42 is connected by a pipe 43 to an absorber 44. Any vapors 10 vented during flash distillation are led by pipe 43 to absorber 44, which absorber uses an absorbent, such as water, which may be injected into the absorber by means of a pipe 46 connecting the absorber with the supply of water 1. The absorber 15 44 may be connected by a pipe 47 to a recycle system into which the stripped vapors vented from the absorber 44 are passed. The reference numerals 10 and 11 indicate metering devices for measuring the quantity of water passed into absorbers 28 and 44.

The gases vented from absorber 28 are led by a pipe 29 from the absorber 28 to an oil-absorber 50 on the top of which is mounted a pipe 45 adapted to carry the stripped gases from the oil 25 absorber out of the system. Pipe 45 may be equipped with suitable control valves and measuring devices. To the absorber 50 is also attached a pipe 51 and pipe 54, which connects the absorber 50, through an oil heater 52 and pipe 54, 30 to a flash chamber 55. A suitable temperature indicating device 53 may be provided in this line to enable a constant temperature of oil to be maintained. The enriched absorber oil leaves absorber 50 by means of the pipe 51 and then 35 passes to oil heater 52 where, by means of temperature indicator 53, sufficient heat is maintained to flash off in the flash chamber 55 the absorbed hydrocarbon without the need of boiling the absorber oil. A cooler 55A may be provided in the flash chamber 55 to cool the gases in the 40 heat thereof. The gases removed from 55, after being cooled by means of the cooler 55A, are passed through pipe 56 to a trap 64. A pipe 66, provided with a metering device 65, is adapted to 45 connect the trap 64 with a gasometer 67. A suitable pipe 15 may be provided for connecting the gasometer 67 to the compressor 16. A suitable valve is provided to regulate the flow of recycle gases to the compressor. Metering devices 50 are also included in this line. The gasometer 67 is employed to maintain a constant flow of gases 55 to the intake of compressor 16.

A flash chamber 55 is connected through pipe 57 with an oil cooler 58, surge tank 59, pump 61 55 and meter 62 and through pipe 63 with the oil absorber 50 thereby forming a cyclic arrangement for the reuse of the denuded oil from flash chamber 55. A suitable reservoir 60 may be provided for maintaining a constant supply of oil in 60 the system.

In dotted lines on the drawing there is shown a system wherein the oil distillation may be operated at a higher range of pressures, which 65 system has some advantage. Instead of reducing the pressure on the oil at 51 to atmospheric conditions, a pressure is maintained in the apparatus through elements 52, 54, 55, 56, 57, 58 and 64. This pressure is lower than the pressure maintained in oil absorber 50 (but only low enough 70 to cause the oil and gases to follow their prescribed courses). A pipe 71 may be provided for connecting the trap 64 to a booster compressor 72. A by-pass 73 having a valve 74 may be provided for conducting the gases around the booster compressor 72. A pipe 75 may be provided to

connect the booster pump or the pipe 73 to the mixer 17. In this modification the gases from trap 64 do not enter the gasometer 67 but instead pass through pipe line 71 and meter 70 to the booster compressor 72. Regulation of fluctuating 5 gas flows is effected by means of by-pass 73 and valve 74. The "boosted" gases leave the compressor 72 by means of pipe 75 and are injected back into the system at 17 instead of at 16 as when using the low pressure gasometer system. 10

In order further to illustrate my invention but without being limited thereto, the following specific example is given.

Example

15

Butane in liquid condition and in amount equivalent to one part by volume of gas (one part by weight) is passed through the heating coil 5 where it is heated to 300° F. Water equivalent to 20 60 volumes of steam (18.5 parts by weight) is introduced through the pipe 2 and is heated in 18 then sent to the mixer 17 where it is mixed with 10 parts by volume of air (5 parts by weight) introduced thereto by means of the pipe 3. The mixture of the three gases passes through the 25 mixer 17 where the temperature is maintained at 550° F. The mixture of air and steam and the butane are caused to travel at high velocity to the point 17 where they are mixed at high turbulence and the butane is immediately raised 30 to the reaction temperature. This mixture is then passed to the reaction chamber 19 and is removed after reaction and quenched by water from the pipe 22, to below the temperature of decomposition, e. g. 300° F., the total time employed for the reaction being about .3 second.

The mixture is then introduced into the cooler 25 and absorber 28 where it is scrubbed and cooled by water introduced by pipe 27, the uncondensed gases passing out through the pressure release pipe 29, while the water and condensed oxygenated compounds leave through the pipe 32 and liquid release valve 31 to the still 35.

Owing to release of pressure in the still 35, 45 upon the addition of sufficient heat if necessary, oxygenated products, such as acetaldehyde, methyl alcohol, acetone, propyl and butyl alcohol, pass off as vapors through the line 39 and after condensation in the condenser 40 are collected in storage tanks 42. This mixture can 50 be readily separated into the individual components by fractional distillation, and may then be purified by suitable chemical treatment if necessary.

The water carrying formadehyde and organic acids leave the chamber 36 by pipe 37 to storage and may be treated to recover and separate its components.

For every part by volume—or weight—butane 60 injected at 4, about seven parts by volume of recycle gas are returned to 16 by line 15 after its recovery from the vent gases leaving absorber 28 by line 29. By way of illustration, it may be stated that the gases leaving absorber 28 are 65 made up of the following:

1.6	CO ₂	16.0	C ₃ H ₈ and C ₄ H ₁₀
8.2	C ₃ H ₈ and C ₄ H ₁₀	70.0	N ₂
3.6	O ₂	1.0	CO

70

After leaving absorber 28 the gases (still under pressure) pass to oil-absorber 50. At this point the oil soluble constituents are absorbed from the N₂, CO, CO₂, etc., and conducted to distillation unit 55. The gases are distilled from 75

the oil absorbent and pass overhead through line 56 to gasometer 67 and then are returned to 16 where they are mixed with fresh butane and sent to the reacting zone for reaction with O₂. The 5 unabsorbed N₂, CO and CO₂ are vented at 45.

By way of illustration and recycling gases may have the following constituents:

	Per cent by volume	Per cent by volume	
CH ₄	8.0	C ₄ H ₁₀	47.0
C ₃ H ₆	14.63	O ₂	1.0
C ₃ H ₈	13.41	CO ₂	1.5
C ₄ H ₆	14.0		

15 And the vent gases may have the following constituents and about 10 volumes are vented for every volume of fresh butane injected:

	Per cent by volume
CO ₂	1.5
CO	3.8
O ₂	2.0
N ₂	92.0

25 By way of illustration of the nature and yield of the products produced, it may be stated that for each 100 pounds of butane treated by the foregoing process, there are produced 23.0 pounds of acetaldehyde, 10 pounds of acetone, 3 pounds of methyl alcohol, 3 pounds of propyl alcohol, 3 pounds of butyl alcohol, 7 pounds of organic acids and 15 pounds of formaldehyde. The acetaldehyde may be oxidized to form acetic acid in a subsequent process.

35 As an example and not as an illustration, there may be used a volume ratio of one part of butane to 10 parts of air to 70 parts of steam which has a weight ratio of 1/5/21.7. This weight of steam, 21.7 pounds, will absorb 11 B. t. u. per degree 40 Fahrenheit. The proportion and temperature of the steam has among other functions, the functions of being a diluting or controlling agent, of acting as a heat carrier by which the heat necessary to initiate the reaction is delivered to 45 the mixture of air and hydrocarbon under the most favorable circumstances and of a protective agent to retard decomposition of the intermediate products, particularly acetaldehyde, after they have first been formed. Other substances 50 may replace steam for some of these functions. It is, however, preferable to use a sufficient quantity of steam to produce all these functions.

55 It is to be understood that the foregoing detailed description is given merely by way of illustration and many variations may be made therein without departing from the spirit of my invention.

Having described my invention, what I desire to secure by Letters Patent is:

60 1. The method of producing oxygenated organic compounds, which comprises subjecting aliphatic hydrocarbons in the vapor phase to oxidation with free oxygen in the presence of at least 30 volumes of steam for each volume of hydrocarbon vapor and in the absence of oxidation catalysts.

65 2. The method of producing oxygenated organic compounds, which comprises subjecting aliphatic hydrocarbons in the vapor phase to oxidation with free oxygen in the presence of at least 30 volumes of steam for each volume of hydrocarbon vapor and in the absence of oxidation catalysts, and rapidly cooling the products.

70 3. The method of producing oxygenated organic compounds, which comprises subjecting all-

5 phatic hydrocarbons in the vapor phase to oxidation under super-atmospheric pressure with free oxygen in the presence of at least 30 volumes of steam for each volume of hydrocarbon vapor and in the absence of oxidation catalysts.

4. Method of producing oxygenated organic compounds, which comprises subjecting aliphatic hydrocarbons in the vapor phase to oxidation under super-atmospheric pressure with free oxygen in the presence of at least 30 volumes of 10 steam for each volume of hydrocarbon vapor and in the absence of oxidation catalysts, and rapidly cooling the products.

5. The method of producing oxygenated organic compounds, which comprises subjecting aliphatic hydrocarbons in the vapor phase to oxidation under super-atmospheric pressure with free oxygen in the presence of at least 30 volumes of 15 steam for each volume of hydrocarbon vapor and in the absence of oxidation catalysts, rapidly cooling the products, separating hydrocarbons from the products, and returning them to the oxidation zone.

6. The method of producing oxygenated organic compounds, which comprises mixing, in 25 the absence of oxidation catalysts, an aliphatic hydrocarbon in the vapor phase and a gas comprising free oxygen at a temperature below that at which the hydrocarbon reacts substantially with free oxygen, with at least 30 volumes of 30 steam for each volume of hydrocarbon vapor, the temperature of the steam being such that the hydrocarbon is raised to a temperature at which it reacts with free oxygen.

7. The method of producing oxygenated organic compounds, which comprises mixing, in 35 the absence of oxidation catalysts, an aliphatic hydrocarbon in the vapor phase and a gas comprising free oxygen at a temperature below that at which the hydrocarbon reacts substantially 40 with free oxygen, with at least 30 volumes of steam for each volume of hydrocarbon vapor, the temperature of the steam being such that the hydrocarbon is raised to a temperature at which it reacts with free oxygen, and after an interval 45 of 0.3 to 0.5 seconds rapidly cooling the mixture.

8. The method of producing oxygenated organic compounds, which comprises mixing, in 50 the absence of oxidation catalysts, an aliphatic hydrocarbon in the vapor phase and air, at a temperature below that at which the hydrocarbon reacts substantially with free oxygen and under super-atmospheric pressure, with steam in amount at least 30 times the volume of the hydrocarbon, also under pressure and at a temperature such that the hydrocarbon is raised to a 55 temperature at which it reacts with free oxygen, and after an interval of 0.3 to 0.5 seconds rapidly cooling the mixture.

9. The method of producing oxygenated organic compounds, which comprises mixing, in 60 the absence of oxidation catalysts, an aliphatic hydrocarbon in the vapor phase and air, at a temperature below that at which the hydrocarbon reacts substantially with free oxygen and under superatmospheric pressure, with steam in amount at least 30 times the volume of the hydrocarbon, also under pressure and at a temperature such that the hydrocarbon is raised to a 65 temperature at which it reacts with free oxygen, after an interval of 0.3 to 0.5 seconds rapidly cooling the mixture, separating hydrocarbons from the mixture, and returning them to the oxidation zone.

10. The method of producing oxygenated or-

ganic compounds, which comprises mixing, in the absence of oxidation catalysts, an aliphatic hydrocarbon in the vapor phase and air, at a temperature below that at which the hydrocarbon 5 reacts substantially with free oxygen and under super-atmospheric pressure, with steam in amount at least 30 times the volume of the hydrocarbon, also under pressure and at a temperature such that the hydrocarbon is raised to a 10 temperature at which it reacts with free oxygen, and after an interval of 0.1 to 3 seconds rapidly cooling the mixture.

11. The method of producing oxygenated organic compounds, which comprises mixing, in 15 the absence of oxidation catalysts, one volume of the vapor of one or more of the lower homologues of methane and 7 to 14 volumes of air at a temperature below that at which the hydrocarbons react substantially with free oxygen and 20 under a pressure between 50 and 200 pounds per square inch, with 30 to 200 volumes of steam under a similar pressure and at a temperature such that the hydrocarbons are raised to a temperature at which they react with free oxygen, 25 and after an interval of 0.3 to 0.5 seconds rapidly cooling the mixture.

12. The method of producing oxygenated organic compounds, which comprises mixing, in 30 the absence of oxidation catalysts, one volume of the vapor of one or more of the lower homologues of methane and 7 to 14 volumes of air at a temperature below that at which the hydrocarbons react substantially with free oxygen and under a pressure between 50 and 200 pounds per 35 square inch, with 30 to 200 volumes of steam under a similar pressure and at a temperature being such that the butane is raised to a temperature at which they react with free oxygen, after an interval of 0.3 to 0.5 seconds rapidly 40 cooling the mixture, separating hydrocarbons from the mixture, and returning them in vapor form to the oxidation zone in amount about 7 times the volume of fresh hydrocarbon entering the zone.

45 13. The method of producing oxygenated organic compounds, which comprises mixing, in the absence of oxidation catalysts, one volume of butane at a temperature of at most about 320° F. and 7 to 14 volumes of air with 30 to 200 volumes 50 of steam, all under a pressure of 20 to 500 pounds per square inch, the temperature of the steam

being such that the butane is raised to a temperature of 550° to 850° F., and after an interval of 0.1 to 3 seconds rapidly cooling the mixture.

14. The method of producing oxygenated 5 organic compounds, which comprises mixing, in the absence of oxidation catalysts, one volume of butane at a temperature of at most about 320° F. and 7 to 14 volumes of air with 30 to 200 10 volumes of steam, all under a pressure of 20 to 500 pounds per square inch, the temperature of the steam being such that the butane is raised to a temperature of 550° to 850° F., after an interval of 0.1 to 3 seconds rapidly cooling the mixture, separating hydrocarbons from the mixture and returning them in vapor form to the 15 oxidation zone, in amount about 7 times the volume of fresh butane entering the zone.

16. The method of producing oxygenated 20 organic compounds, which comprises mixing, in the absence of oxidation catalysts, one volume of butane at a temperature of at most about 320° F. and 7 to 14 volumes of air, with 50 to 100 25 volumes of steam, all under a pressure of 50 to 200 pounds per square inch, the temperature of the steam being such that the butane is raised to a temperature of 750° to 800° F., after an interval of 0.1 to 3 seconds rapidly cooling the mixture, separating hydrocarbons from the mixture and returning them in vapor form to the 30 oxidation zone, in amount about 7 times the volume of fresh butane entering the zone.

16. The method of producing oxygenated 35 organic compounds, which comprises mixing, in the absence of oxidation catalysts, an aliphatic hydrocarbon in the vapor phase and a gas comprising free oxygen at a temperature below that at which the hydrocarbon reacts substantially with free oxygen, with at least 30 volumes of steam for each volume of hydrocarbon vapor, the 40 temperature of the steam being such that the hydrocarbon is raised to a temperature at which it reacts with free oxygen, flashing off vapors and gases from the resulting products, absorbing the 45 soluble constituents of the flashed vapors and gases in an oil, venting from the system the unabsorbed fraction of the vapors and gases, heating the oil to liberate the absorbed materials, and returning the liberated materials with fresh 50 hydrocarbon, air and steam to the oxidation zone.

JOSEPH ELLIOTT BLUDWORTH.

CERTIFICATE OF CORRECTION.

Patent No. 2,128,909.

September 6, 1938.

JOSEPH ELLIOTT BLUDWORTH.

It is hereby certified that error appears in the printed specification of the above numbered patent requiring correction as follows: Page 5, first column, line 37, claim 12, strike out the word "being" and for "butane is" read hydrocarbons are; and that the said Letters Patent should be read with this correction therein that the same may conform to the record of the case in the Patent Office.

Signed and sealed this 25th day of October, A. D. 1938.

Henry Van Arsdale

(Seal)

Acting Commissioner of Patents.

ganic compounds, which comprises mixing, in the absence of oxidation catalysts, an aliphatic hydrocarbon in the vapor phase and air, at a temperature below that at which the hydrocarbon 5 reacts substantially with free oxygen and under super-atmospheric pressure, with steam in amount at least 30 times the volume of the hydrocarbon, also under pressure and at a temperature such that the hydrocarbon is raised to a 10 temperature at which it reacts with free oxygen, and after an interval of 0.1 to 3 seconds rapidly cooling the mixture.

11. The method of producing oxygenated organic compounds, which comprises mixing, in 15 the absence of oxidation catalysts, one volume of the vapor of one or more of the lower homologues of methane and 7 to 14 volumes of air at a temperature below that at which the hydrocarbons react substantially with free oxygen and 20 under a pressure between 50 and 200 pounds per square inch, with 30 to 200 volumes of steam under a similar pressure and at a temperature such that the hydrocarbons are raised to a temperature at which they react with free oxygen, 25 and after an interval of 0.3 to 0.5 seconds rapidly cooling the mixture.

12. The method of producing oxygenated organic compounds, which comprises mixing, in 30 the absence of oxidation catalysts, one volume of the vapor of one or more of the lower homologues of methane and 7 to 14 volumes of air at a temperature below that at which the hydrocarbons react substantially with free oxygen and under a pressure between 50 and 200 pounds per 35 square inch, with 30 to 200 volumes of steam under a similar pressure and at a temperature being such that the butane is raised to a temperature at which they react with free oxygen, after an interval of 0.3 to 0.5 seconds rapidly 40 cooling the mixture, separating hydrocarbons from the mixture, and returning them in vapor form to the oxidation zone in amount about 7 times the volume of fresh hydrocarbon entering the zone.

45 13. The method of producing oxygenated organic compounds, which comprises mixing, in the absence of oxidation catalysts, one volume of butane at a temperature of at most about 320° F. and 7 to 14 volumes of air with 30 to 200 volumes 50 of steam, all under a pressure of 20 to 500 pounds per square inch, the temperature of the steam

being such that the butane is raised to a temperature of 550° to 850° F., and after an interval of 0.1 to 3 seconds rapidly cooling the mixture.

14. The method of producing oxygenated 5 organic compounds, which comprises mixing, in the absence of oxidation catalysts, one volume of butane at a temperature of at most about 320° F. and 7 to 14 volumes of air with 30 to 200 10 volumes of steam, all under a pressure of 20 to 500 pounds per square inch, the temperature of the steam being such that the butane is raised to a temperature of 550° to 850° F., after an interval of 0.1 to 3 seconds rapidly cooling the mixture, separating hydrocarbons from the mixture and returning them in vapor form to the 15 oxidation zone, in amount about 7 times the volume of fresh butane entering the zone.

16. The method of producing oxygenated 20 organic compounds, which comprises mixing, in the absence of oxidation catalysts, one volume of butane at a temperature of at most about 320° F. and 7 to 14 volumes of air, with 50 to 100 25 volumes of steam, all under a pressure of 50 to 200 pounds per square inch, the temperature of the steam being such that the butane is raised to a temperature of 750° to 800° F., after an interval of 0.1 to 3 seconds rapidly cooling the mixture, separating hydrocarbons from the mixture and returning them in vapor form to the 30 oxidation zone, in amount about 7 times the volume of fresh butane entering the zone.

16. The method of producing oxygenated 35 organic compounds, which comprises mixing, in the absence of oxidation catalysts, an aliphatic hydrocarbon in the vapor phase and a gas comprising free oxygen at a temperature below that at which the hydrocarbon reacts substantially with free oxygen, with at least 30 volumes of steam for each volume of hydrocarbon vapor, the 40 temperature of the steam being such that the hydrocarbon is raised to a temperature at which it reacts with free oxygen, flashing off vapors and gases from the resulting products, absorbing the 45 soluble constituents of the flashed vapors and gases in an oil, venting from the system the unabsorbed fraction of the vapors and gases, heating the oil to liberate the absorbed materials, and returning the liberated materials with fresh 50 hydrocarbon, air and steam to the oxidation zone.

JOSEPH ELLIOTT BLUDWORTH.

CERTIFICATE OF CORRECTION.

Patent No. 2,128,909.

September 6, 1938.

JOSEPH ELLIOTT BLUDWORTH.

It is hereby certified that error appears in the printed specification of the above numbered patent requiring correction as follows: Page 5, first column, line 37, claim 12, strike out the word "being" and for "butane is" read hydrocarbons are; and that the said Letters Patent should be read with this correction therein that the same may conform to the record of the case in the Patent Office.

Signed and sealed this 25th day of October, A. D. 1938.

Henry Van Arsdale

(Seal)

Acting Commissioner of Patents.
